F. KOELLIKER ET AL.

AMUSEMENT DEVICE

Filed Sept. 27, 1921

UNITED STATES PATENT OFFICE.

FREDERICK KOELLIKER AND FRANK LABIN, OF BELLEVUE, PENNSYLVANIA; SAID KOELLIKER ASSIGNOR TO SAID LABIN.

AMUSEMENT DEVICE.

Application filed September 27, 1921, Serial No. 503,520.

To all whom it may concern:

Be it known that we, FREDERICK KOELLIKER and FRANK LABIN, citizens of the United States, residing at Bellevue, in the county of Allegheny and State of Pennsylvania, have jointly invented a new and useful Improvement in Amusement Devices, of which improvement the following is a specification.

10 Our invention relates to that class of amusement devices, of toy character, which are rotated about a common center.

Among the objects of our invention are to produce a device of the above character, in which a plurality of swinging conveyances for containing dummy figures are rotated about a common center; which is simple in construction; of few parts; can be cheaply manufactured, and having certain new and 20 novel features of construction, combination and arrangement of parts as will be herein-after set forth in this specification and particularly pointed out in the appended claims.

In the accompanying drawings, forming a 25 part of this specification, we have shown one embodiment of our invention, in which—

Figure 1 is a side elevation of the device, a part of which is in section.

Fig. 2 is a plan thereof.

30 Fig. 3 is an enlarged sectional side elevation of a fragmentary portion of the device as it would appear when the spring power is spent; and

Fig. 4 is a similar view of said part, 35 taken at right angles thereto, with power spring in position for operation.

The device comprises a suitable support including a base 1, having a hollow vertically-disposed column 2, preferably of 40 square form in cross section and a centrally disposed canopy 3 secured thereto about midway its length. Within the column 2 is loosely arranged the operating rod and spring for actuating same. This rod is 45 formed, preferably, of a flat strip of metal twisted into a spiral 4 having at its lower end a fixed plate 5, preferably square in form, the upper end thereof being suitably formed, as in a ring 6. Disposed about this 50 spiral rod is the spiral spring 7, which engages the plate 5 at one end and the head of the column at the other. Resting on top of the column is a horizontally-disposed circularly formed rotary carrier 8, the spiral rod

passing freely through a centrally-disposed 55 opening therein. This carrier is provided with automatic means for engaging the spiral to operate the carrier and for releasing said spiral when elevated as hereinafter set forth. The automatic means comprises a 60 pair of spaced guide members 9, of like form, pivotally or hingedly attached to the carrier with their operating surfaces in parallel relation. The relation of these surfaces with one another are such that they 65 are spaced but a trifle greater apart than the thickness of the strip of which the spiral rod is formed and function as guides between which the rod operates.

Suspended by wire rods 10, which are 70 hingedly attached to the lugs 11 fixed to the carrier, are the members or conveyances 12, which are adapted to contain suitable dummies (not shown).

To operate the device, the spiral rod is 75 drawn up, by means of the ring 6, as far as possible thus compressing the spring 7, as shown in Fig. 4. As this rod is elevated it causes the guide members, 9, to automatically trip upwardly, as shown by dotted lines 80 in Fig. 3, to permit such elevation without moving the carrier 8. On releasing the rod the guide members automatically return to their engagement position with the spiral, as shown by full lines in Fig. 3. As soon as these guides, 9, are in engaged position, 85 the tension of the spring, 7, exerts a downward pull on the rod and as it passes between the guides, 9, which are fixed to the rotary carrier, causes rotation of said carrier and conveyances suspended therefrom.

This rotation is maintained as long as there is active tension of the spring and the time required for the lower end of the rod to come to rest at the bottom of the column. Due to 95 the friction between the rod and guides, as well as the resistance offered by the conveyances, during rotation, such rotation is somewhat retarded, causing a rate of speed of about thirty revolutions per minute, in 100 a full sized device, and of a duration of about twenty seconds, depending, of course, on the length and tension of the spring and length of the rod. By simply raising the spiral rod, 4, by the ring, 6, the device is 105 again wound up for further operation.

Various modifications and changes in the details and arrangement thereof may be

made in the device without departing from the spirit and scope of the invention and be within the appended claims.

We claim as our invention and desire to 5 secure by Letters Patent:

1. In an amusement device, a support, a longitudinally movable spiral rod disposed therein, a rotatable carrier mounted on said support and through which said rod extends, and means on said carrier adapted to engage said rod for rotation of the carrier on longitudinal movement of said rod. 10
2. In an amusement device, a support, a longitudinally movable spiral rod disposed therein, a rotatable carrier mounted on said support and through which said rod extends, and members on said carrier, automatically engaging said rod to rotate the carrier on longitudinal movement of said rod. 15
3. In an amusement device, a support, a longitudinally movable spiral rod disposed therein, a carrier mounted on said support and rotatable during longitudinal movement of said rod in one direction, and rod 20 engaging means on said carrier for effecting rotation thereof on longitudinal movement of said rod.
4. In an amusement device, a support, a longitudinally movable spiral rod disposed therein, a rotatable carrier mounted on said support and through which said rod extends, a plurality of spaced members hingedly suspended from said carrier, and means on said carrier for engaging said rod to rotate said carrier on movement of the rod. 25
5. In an amusement device, a support, a carrier rotatably mounted thereon, a rod 30

longitudinally movable in said support and disposed through said carrier, operative connection between said rod and carrier for rotation of the carrier on longitudinal movement of the rod, and means in said support for longitudinally moving said rod. 40

6. In an amusement device, a support, a carrier rotatably mounted thereon, a longitudinally movable rod housed in said support and extending through said support and carrier, a spring in said support and compressible between a portion of said rod and support, and means on said carrier engaging said rod for rotation of the carrier on expansion of said spring. 45 50

7. In an amusement device, a base, a substantially cylindrical support extending thereabove, a carrier rotatably mounted at the top of said support, a longitudinally movable rod housed within said support and extending through said support and carrier, a spring in said support and compressible between the lower end of said rod and the top of said support, and means disposed on the carrier and engaging said rod for rotation of said carrier on longitudinal movement of said rod under expansion of said spring. 55 60

In testimony whereof, we have hereunto signed our names in the presence of two subscribing witnesses.

FREDERICK KOELLIKER.
FRANK LABIN.
